RESILIENT SUPPORT

Harvey B. Lawton, Bloomington, Ill., assignor to
 Williams Oil-O-Matic Heating Corporation,
 Bloomington, Ill., a corporation of Illinois

Application June 28, 1934, Serial No. 732,755

2 Claims. (Cl. 248—26)

This invention relates to improvements in resilient supports and more particularly to a means for resiliently supporting an electric or other motor to absorb the vibrations set up in the motor frame when the motor is in operation.

With this and other objects in view, reference is made to the accompanying sheet of drawing which illustrates a preferred form of this invention with the understanding that detail changes may be made without departing from the scope thereof.

In the drawing:

Figure 1 is a fragmentary view in end elevation of a preferred embodiment of this invention with the upper part of the motor case broken away.

Figure 2 is a view in front elevation of Figure 1.

Figure 3 is an enlarged detail view of one of the supports, partly in section, taken on the line 4—4 of Figure 1.

Figure 4 is a projected view in perspective of the vibration-absorbing members.

The embodiment of this invention is illustrated as applied to an electric motor of a type in which the stator 1 is mounted between end plates or end bells 2 and 3 held together on each side of the stator by bolts 4. Each end bell is provided with similarly spaced-apart radially depending feet 5 which are mounted on flat springs 6 preferably bent back upon themselves to form loop portions 7, 30 and the adjacent end portions 8 are secured to a base plate 9. The plate 9 extends between and below the end bells 2 and 3, as shown in Figure 1, and is preferably provided with struck-up portion 10, as shown in Figure 2. The base plate 9 extends slightly in advance of the resiliently-mounted feet of the end bell and is preferably provided with a slot 11 for attachment.

As shown in Figure 5, each foot terminates in a flat surface approximately forty-five degrees (45°) to the horizontal and is provided with a screw-threaded headed retaining bolt 12 threaded axially into each foot to secure the vibration-absorbing medium in place. The vibration-absorbing medium, as shown in the projected perspective view in Figure 4, includes a shouldered perforated member 13 and an annular member 14 adapted to receive the portion 15 of the member 13, as shown in Figure 3. It is preferable to form the resilient vibration absorbing members 13 and 14 of a resilient substance such as gum rubber or caoutchouc. It is preferable to mount members 13 and 14 on each foot 5 and upon the free end of the flat spring 6, as shown in detail in Figure 3. The free end of the flat spring 6 is

provided with a perforation adapted to receive the cylindrical extension 15 of the member 13, and it is preferable in assembling the parts, as shown in Figure 3, to insert a washer 16 between the annular flange of the portion 13 and the spring 6, then cause the annulus 14 to engage the portion 15 and the adjacent surface of the flat spring 6. It is also preferable to insert a washer 17 between the member 14 and the foot 5 and a washer 18 between the outer surface of the member 13 and the headed bolt 12. When the parts are assembled, as above described and shown in Figure 3, the bolt 12 is taken up to hold them in close contact. The flat spring 6 is preferably provided with a portion 19 bent at right angles 15 to the end in engagement with the resilient vibration absorbing members 13 and 14, which is continued to form the loop 7 overhanging the edge of the struck-up portion 10 of the base plate 9 and then extended along the top of the struck-up portion 10 to which it is preferably secured by rivets 20. By this construction and formation of the spring 6, the respective springs will absorb the major vibrations of the motor or the vibrations of greatest duration while the resilient members 13 25 and 14 will absorb the minor vibrations or those of less duration, so that little, if any, vibration is transmitted through the feet and springs to the base plate 9.

What I claim is:

1. In a vibration absorbing support for an electric motor, including a stator mounted between end plates with each of said end plates provided with similar spaced-apart radially depending feet terminating in flat surfaces approximately forty-five degrees to the vertical, the combination with a base arranged under each end plate having struck-up parallel medial portions between said feet, of spring members looped back upon themselves having opposite ends provided with flat surfaces with one secured upon the said raised portion of the base and the other secured to the angular surface of the adjacent foot and with the loop of the spring extending downwardly over said raised portion of the base in parallel relation 45 to the axis of the adjacent foot.

2. The structure of claim 1, wherein the spring securing means includes an axial retaining bolt passing through a retaining washer and flat spring end into each foot with members of resilient vibration absorbing material interposed between the angular surface of the foot and retaining washer on each side of the spring.

HARVEY B. LAWTON.
